UNITED STATES PATENT OFFICE.

BENJAMIN M. ROLPH, OF DIXON, ILLINOIS.

DITCHING-MACHINE.

1,252,496.

Specification of Letters Patent. Patented Jan. 8, 1918.

Application filed November 23, 1916. Serial No. 132,930.

To all whom it may concern:

Be it known that I, BENJAMIN M. ROLPH, a citizen of the United States, residing at Dixon, in the county of Lee and State of Illinois, have invented certain new and useful Improvements in Ditching-Machines, of which the following is a specification.

My invention pertains to ditching machines, of that class which are self-propelled, and which accomplish the work of excavating by means of a series of scoops mounted on a rotatable wheel, such as is shown in Letters Patent of the United States issued to myself May 12, 1908, numbered 887,129.

One of the purposes of the present invention is to provide a movable frame for the support of the excavating wheel which will always be maintained in a horizontal position.

Another purpose thereof is to form the scoops with self-cleaning devices of a novel and useful character.

Another object of my device is the provision of a shoe or follower in rear of the wheel which is susceptible of operation independently of the wheel-carrying frame.

These and other advantages of my invention will more fully appear in the following specification, reference being had to the drawings accompanying the same, in which,

Figure 1 is a side elevation of the left side of the machine. Fig. 2 is a similar view of the right side thereof. Fig. 3 shows one of the scoops 34 in medial longitudinal section. Fig. 4 is a rear end view thereof. Fig. 5 shows the arm 40, in detail. Fig. 6 is a detached view of the agitator 38. Fig. 7 is a side elevation of the shoe 44 and supporting mechanism. Fig. 8 is a rear elevation thereof.

Similar parts are indicated by corresponding reference numbers throughout the several figures.

1 represents the main frame of the machine, supported on carrying wheels 2, and 3 is an auxiliary frame having connecting arches 4, united by bars 5, and connected with the front part of the frame members 3 by braces 6. The forward end of the frame 3 is supported by means of cables 7 attached thereto and passing upwardly over rollers 8 on supports 9 fixed to the frame 1, and thence downwardly under rollers 10 on the frame 1 to a pair of drums 11 on a shaft 12 at the rear end of the frame 1. Said drums are on the outside of the frame, and only

one thereof is shown in the drawings. (Fig. 2.) The rear end of the frame 3 is supported by a pair of cables 13 connected therewith and passing upwardly over rollers 14 on posts 15 mounted on the frame 1, and thence downwardly to a pair of drums, (not shown) on the shaft 12, on the inside of the frame 1. The shaft 12 can be rotated by usual clutch connections with the main shaft 65 of the motor, to raise or lower the frame 3 at will.

At its forward end the frame 3 is provided on each side with rollers 16, which are engaged by arc-shaped guides 17 fixed to the frame 1, and the rear end of the frame 3 has rollers 18 operating on the faces of arcs 19 secured near the rear end of the frame 1. Mounted on the frame 1 is a main-drive-shaft 20, which is located centrally of a circle of which the guide 17 forms a part, and by this means in the upward and downward movement of the frame 3, the operating mechanism carried thereby is maintained throughout in the same relative position 80 with regard to the shaft 20.

21 represents the rim of a ditching wheel which is supported rotatably in the frame 3 by means of a wheel 22 on a shaft 23 on said frame, and a gear wheel 24 on a shaft 25 on the frame 3, engaging a gear-ring 26 on the inner face of the rim 21. An arm 27 extends downwardly from the frame 3 and is provided at its lower end with a wheel 28 which engages the inner face of the rim 21 90 and assists in steadyng the same. On one end of the drive-shaft 20 is a sprocket gear-wheel 29 actuated by a sprocket-chain 30 from a similar gear-wheel 31 on the main motor shaft 32, the motor being mounted on the rear end of the frame 1, and inclosed in a casing 33. Movement is imparted from the shaft 20 to the shaft 25 to cause a rotation of the wheel 21 by means of suitable gearing, similar to that shown and described in said former patent, and also to operate the propelling devices of the machine, such parts not being specifically novel nor involved in the present application.

A series of scoops 34 is supported outwardly from the rim 21, by means of arms 35 at the forward ends of the scoops and at their rear ends by means of bearings 36 on the rim 21 and bearings 37 on the inner faces of the scoops, between which bearings 110 are rotatably held agitators 38, each formed of a plurality of blades 39, and adapted to

be actuated by a spring-arm 40, secured to the inner face of the brace 6 on the right side of the machine. As each of the scoops reaches a point near the top of the wheel 21 the arm 40 engages one of the blades 39 of the agitator carried by such scoop, giving thereto a quick whirling movement, and dislodging any dirt that is retained in the end of the scoop. The scoops are preferably of 10 open construction, and are practically self-cleaning, but sometimes in working in heavy soil there is a tendency of the earth to stick in the scoop, especially in the rear end thereof, where it is necessary to have some kind 15 of a gate or closure. The agitators 38 provide a sufficient obstruction to hold the material when the scoop is being filled, and at the same time successively dislodge the same at the desired point in the rotation of 20 the wheel. The arm 40 is spring-supported so as to prevent breakage in case a small boulder or other obstruction should become lodged in the end of the scoop, against the agitator.

25 Mounted on the rear part of the frame 3 are cross-pieces 41, from which are supported an arc-shaped plate 42 and braces 43 therefor. A shoe 44, corresponding in shape with the plate 42, is supported therefrom by 30 means of a short tongue 45 on the shoe passing through a longitudinal slot 46 in the support 42, and provided on the inner end with an eye 48 adapted to receive the threaded end of a rod 49, provided near its upper 35 end with a bearing 50 resting on a plate 51 mounted on the cross-pieces 41. The upper end of said rod also has a hand-wheel 52 by means of which it can be rotated. The rotation of said rod results in the raising 40 or lowering of the shoe 44, as desired. When the excavating wheel is in operation the shoe 44 follows closely behind the same, preventing the earth from falling back into the trench. When an obstruction of con- 45 siderable size is encountered by the excavating wheel, it is necessary to raise the same and pass over the obstruction. It has heretofore been necessary to move the machine

ahead several feet, in order to clear not only the wheel and scoops, but the shoe in rear 50 thereof, but with the adjusting devices above set forth when the wheel is raised to clear an obstacle the shoe 44 is raised still higher, permitting the excavating operation to be continued just beyond the obstacle. After 55 the machine has progressed a sufficient distance the shoe is again lowered to operative position. By this means it is not necessary to clean out so much of the ditch by hand.

What I claim as my invention and desire 60 to secure by Letters Patent of the United States, is:

1. In combination with a portable frame and ditching wheel mounted therein, a scoop mounted on said wheel so as to revolve therewith, provided at its rear end with an agitator wheel adapted to rotate in the line of movement of said scoop around said wheel, and normally forming a stop for the end of 65 said scoop.

2. The combination with a portable frame and ditching wheel rotatably mounted therein, of a plurality of scoops secured to the periphery of said wheel, each provided in its rear end with an agitator wheel adapted to rotate in the line of movement of said scoops; and means for rotating each of said agitator wheels, in succession, at a predetermined point in the rotation of said ditching wheel.

3. In a device of the class described, a portable frame; an excavating wheel rotatably mounted in said frame; a plurality of scoops secured to said wheel; agitators in the rear ends of said scoops formed of a plurality of blades rotatably mounted; and a spring-arm secured to said frame and adapted to successively engage said agitators to suitably operate the same at a desired point in the rotation of said wheel.

In testimony whereof I affix my signature in the presence of two witnesses.

BENJAMIN M. ROLPH.
